Primary Examiner — Elizabeth J Oswecki(74) *Attorney, Agent, or Firm* — Baker & Hostetler LLP(57) **CLAIM**

The ornamental design for a fare collection box, as shown and described.

DESCRIPTION

FIG. 1 is a front perspective view of a fare collection box, showing my new design;

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof.

The broken lines shown in the drawings represent portions of the fare collection box that form no part of the claimed design.
